PRINTING TELEGRAPH APPARATUS

Carl A. Levin, Chicago, Ill., assignor to Teletype Corporation, Chicago, Ill., a corporation of Delaware

Application December 30, 1939, Serial No. 311,767,
which is a division of application Serial No.
204,038, April 25, 1938. Divided and this applica-
tion February 27, 1941, Serial No. 380,911

5 Claims. (Cl. 197—53)

This invention relates to printing telegraph apparatus and more particular to printing telegraph apparatus in which the characters are printed from type elements carried upon the periphery of a rotatable and selectively arrestable type wheel.

This application is a division of application Serial No. 311,767, filed December 30, 1939, by C. A. Levin which is a division of C. A. Levin application Serial No. 204,038, filed April 25, 1938, and now Patent No. 2,230,463, issued February 4, 1941.

An object of the invention resides in the provision, in a printing telegraph receiving unit embodying a type wheel having displaceable type elements, of instrumentalities for actuating said elements, capable of extremely rapid positive operation.

The invention features apparatus for actuating the individual type elements of a type wheel including a print hammer which is actuated by a cam follower and having a yieldable element included in the linkage interposed between the print cam and the print hammer whereby the actual printing operation is performed by the expenditure of kinetic energy of the print hammer and possibly an additional element or elements, such kinetic energy resulting in overtravel of the print hammer permitted by the yieldable element.

According to the present invention, a reciprocatable printing member is provided for actuating the type elements individually. A bail carries the follower roller which engages the periphery of a printing cam, the bail being biased into engagement with the cam by a tension spring. Operation of the printing member is effected when the printing bail cam follower roller rides down an abrupt drop in the printing cam. The distance through which the printing bail is operated by its spring is insufficient to bring the printing member into engagement with a type element. A spring is interposed between the printing bail and the printing member, and the inertia of the element to which motion is imparted by the printing bail causes that element to overtravel, the interposed spring yielding and permitting the overtravel, and the amount of overtravel being sufficient to cause a selected type element to effect printing. The spring which yields and permits the overtravel immediately retracts the printing element to unoperated position, thereby clearing the path of unoperated type elements so that the type wheel may be rotated to a new position.

The type wheel used with this improved type actuating mechanism may be of any suitable construction but preferably is the type wheel shown in detail and claimed in the copending 5 application of C. A. Levin, Serial No. 311,767, filed December 30, 1939, of which this application is a division. In this preferred form of type wheel, the drum portion which joins the upper and lower flanges has a peripheral rib intermediate the upper and lower flanges. The rib thus divides the surface of the drum into two peripheral grooves which serve as seats for the garter springs and confine the springs in the desired position. The type wheel is otherwise 10 substantially the same as that shown in Patent 15 No. 2,180,360 of November 21, 1939 to H. L. Krum et al.

For a complete understanding of the invention reference may be had to the following detailed description to be interpreted in the light 20 of the accompanying drawing wherein

Fig. 1 is a plan view of a portion of a printing telegraph apparatus with parts broken away to show more clearly the features of the printing 25 mechanism according to the present invention;

Fig. 2 is a fragmentary detail perspective view of the type actuating mechanism; and

Fig. 3 is a view partly in elevation and partly 30 in section showing details of the type pallet operating mechanism or printing mechanism and of the type wheel, the type pallet operating mechanism being shown in elevation and the type wheel being shown in section.

In the embodiment of the invention to be described hereinafter, the details of the printing telegraph apparatus which co-operate with the apparatus of the present invention but which do not constitute a part of the combination comprising the invention have not been shown in the drawing and will not be described herein since they are shown and described in great detail in the patent to Albert H. Reiber, No. 2,247,408, July 1, 1941, and are not essential to an understanding of the present invention.

45 Referring to the drawing, wherein like reference characters designate the same parts throughout the several views, the reference numeral 26 designates a print hammer operating lever which is in the form of a bell crank lever 50 and comprises arms 27 and 28. The free end of the arm 27 supports a cam follower roller 29 which engages the periphery of a print controlling cam 31 which may be identical with the print controlling cam of the Reiber patent, 55 above identified, and may operate in exactly the

same manner and according to the same timing as the controlling cam of said Reiber patent. The lever 26 is pivoted on a pivot rod 25, provided at its upper end with a retaining screw 32 which serves to retain a bell crank 37 in place. Arm 28 of lever 26 is provided with an arcuate slot 33, the center of the arc of which coincides with the pivotal axis of lever 26 which is the axis of pivot rod 25. A clamping screw 34 extends through slot 33 and is threaded in one arm 36 of the bell crank lever 37. Bell crank 37 is pivoted on the pivot rod 25 coaxially with lever 26, the screw 32 serving as the upper pivot for the bell crank 37 on pivot rod 25. Arm 36 of bell crank 37 rests upon arm 28 of bell crank 26 and screw 34 clamps the two arms rigidly together, the slot 33 affording provision for angular adjustment of bell crank lever 37 relative to bell crank lever 26. Bell crank 37 has an arm 38 disposed in a horizontal plane considerably above that in which arm 36 is located and approximately in the plane of the type wheel with which the present type actuating mechanism is to co-operate. A vertical bar 39 integral with arms 36 and 38 interconnects the two arms and completes the bell crank 37. Upper arm 38 of bell crank 37 is provided with a plurality of apertures 41 any one of which may receive one end of a tension spring 42, the other end of which is connected to a stationary bracket 43. Spring 42 biases bell crank 37 in a counterclockwise direction and thus urges the cam follower roller 29 into engagement with the periphery of cam 31. Spring 42 furnishes the power for actuating the type pallet of the type wheel and by shifting the foremost end of spring 42 from one to another of the holes 41, the tension of spring 42 may be increased or decreased as desired and, correspondingly, its effect upon the type hammer to be described will be varied. It should be noted that roller 29 is shown in Fig. 1 at the high point of cam 31 just before the roller passes off the high spot, whereas in Fig. 2 the roller is engaging the low point of the cam.

At its free end, arm 38 of bell crank 37 carries a screw 44 (Fig. 3) which supports a spring post 46. A print hammer or type pallet operating member 47 is provided in its foremost end with an open ended slot 48 which fits over the screw 44, the forward end of print hammer 47 resting upon arm 38 of bell crank 37. Print hammer 47 is guided and further supported for reciprocation by a bracket 49 which may be similar to the bracket provided for guiding the print hammer in the Reiber patent above identified. A tension spring 51, which has one end engaging the print hammer 47 and the other end engaging the spring post 46, urges print hammer 47 to its extreme position of retraction which may be determined by the engagement of the closed end of the slot 48 with the screw 44 or by the engagement of a laterally extending projection 52 of the print hammer 47 with an adjustable eccentric 53 secured to a plate 17 which supports ribbon spools 16. Print hammer 47 is provided with a shoulder 54 which comes into engagement with the adjustable eccentric 53 when the print hammer is reciprocated rearwardly of the printing telegraph receiving unit to limit the operating strokes of the print hammer and prevent excessive reciprocation of the type pallet.

In Fig. 1, the printing mechanism is shown in the condition which exists just before a printing operation, bail 26 and bell crank 37 being

in their extreme clockwise position and the free end of the print hammer 47 being retracted well back from the type pallet. As cam follower roller 29 traverses the drop-off in cam 31, lever 26 and bell crank 37 are rocked by spring 42 to their extreme counterclockwise position, the movement to this position being relatively sharp. Screw 44 engages the inner or closed end of the slot 48 in the print hammer 47 and positively moves the print hammer toward the inner end of the type pallet which is aligned with the hammer at that time. The positive movement of the print hammer 47 by bell crank 37 ceases when the cam follower roller 29 engages the innermost portion of the periphery of cam 31, and the termination of the positive movement occurs just before the free end of the print hammer 47 engages the type pallet aligned with it. The inertia of the print hammer 47 causes the hammer to continue to move rearwardly or toward the back of the printing unit after the bell crank 37 has been arrested, the inner end of slot 48 moving away from screw 44 and spring 51 yielding to permit the additional or overtravel movement of the print hammer.

The overtravel of the print hammer 47 is sufficient to drive the type pallet in front of it radially of the type wheel to effect printing, the free end of the print hammer 47 moving into the space between the type pallets on either side of the one actuated. As soon as the kinetic energy of print hammer 47 has been dissipated, spring 51 retracts the print hammer until the inner end of the slot 48 engages screw 44 or until projection 52 engages eccentric 53, and such retraction is sufficient to withdraw the free end of the print hammer from between the type pallets even though the rotation of the cam 31 may not have been sufficient to begin the movement of the bail 26 and bell crank 37 in a clockwise direction. From the foregoing it will be apparent that printing is accomplished by overtravel of the print hammer in a manner decidedly different from that shown in the aforementioned patent to Albert H. Reiber and that only the print hammer 47 overtravels whereas in the embodiment shown and defined in the Reiber patent the bell crank to which the print hammer is attached also overtravels.

Although as pointed out hereinbefore any suitable type wheel may be utilized with the type actuating mechanism described herein, the type wheel which is preferably used is the one covered in the copending application of C. A. Levin, Serial No. 311,767, filed December 30, 1939. As clearly shown in Fig. 3 the type wheel is designated generally by the reference numeral 66 and comprises a foundation in the form of a cast or turned wheel which may comprise upper and lower flanges 61 and 62 respectively joined by an integral drum portion 63. The inner surface of the drum portion 63 is cylindrical and the external drum surface includes a ridge 64 integral with the drum portion 63 and located midway between the flanges 61 and 62. The face of ridge 64 may be flat and the sides thereof are curved toward the flanges 61 and 62, the inner faces of which also curve to meet the curving sides of ridge 64 and form therewith spaced annular grooves of semi-circular cross section. A plurality of radially directed type pallet slots is provided in the type wheel 66, the slots being cut entirely through the drum portion 63 but only partially through the thickness of flange 61.

Each of the slots in the type wheel receives

and slidably supports the shanks 66 of two type pallets 67. The type pallet shanks 66 extend into the interior of type wheel 86 sufficiently far that they may be engaged and actuated by the print hammer 47 to effect printing. The type pallets 67 in the upper row have their shanks 66 notched as shown at 68, the notches opening downwardly, and those in the lower row have similar notches 68 which open upwardly. A garter spring 69 extends through all of the notches 68 of the type pallets 67 in a row and biases them to their innermost position radially of the type wheel. The annular ridge 64, which in cooperation with the inner faces of the flanges 61 and 62 defines the peripheral groove mentioned hereinbefore, separates the garter springs 69 and maintains them in the desired position. When any type pallet 67 is driven outwardly radially of the type wheel 86 by the print hammer 47 the garter spring 69 which engages the shank of the type pallet distends slightly, thus permitting movement of the type pallet, and thereafter restores the pallet to the innermost position.

In this manner, any time that a print hammer 47 is driven forward by its cam and then snapped rearwardly by the spring 42 when the roller 28 moves off the high portion of the cam 31, the type printing hammer will cause a type pallet in alignment with it to be snapped outwardly against a page of paper on a platen 24. The type wheel 86 is suitably positioned on a type wheel support 83 and may be moved to position where the print hammer 47 will be in alignment with either the upper or lower row of type pallets in the type wheel so that either the upper or lower case characters may be printed, all in the manner more fully described in the patent to Reiber mentioned hereinbefore.

Although a specific embodiment of the invention has been described herein, it will be understood that the invention is not limited to such a specific form but is capable of adaptation, modification and rearrangement and is therefore to be limited only by the scope of the appended claims.

What is claimed is:

1. In a printing telegraph apparatus, a type wheel having radially reciprocatable type elements, an operating cam, a cam follower lever, a bell crank pivoted coaxially with said cam follower lever, means for adjustably clamping said bell crank lever to said cam follower lever, spring means associated with said bell crank lever for urging said cam follower lever into engagement with its operating cam, a reciprocatable print hammer member having one end engaging said bell crank lever and the other end disposed inside said type wheel adjacent to the type elements, and a yield spring interconnecting said print hammer and said bell crank.

2. In a printing telegraph apparatus, a type wheel having radially reciprocatable type elements, a cyclically operable cam, a cam follower lever movable between extreme clockwise and counterclockwise positions under the control of

said cam, a bell crank lever having its axis coaxial with that of said follower lever, means for adjustably clamping said bell crank lever to said cam follower lever, means associated with said bell crank lever for urging said cam follower lever into engagement with said cam, a reciprocatable print hammer for reciprocating said type elements individually, said print hammer having pin and slot connection with said bell crank lever, and yieldable means interconnecting said print hammer and said bell crank lever and normally tending to keep said print hammer in a position of extreme retraction with respect to said bell crank lever, said yieldable means enabling said print hammer to overtravel by the expenditure of kinetic energy after having been moved positively a predetermined distance by said bell crank lever.

3. In a printing telegraph apparatus, a plurality of type elements, a print hammer for operating said elements, an actuating lever for said print hammer, resilient means for urging said print hammer into abutting relationship with said actuating lever, and means to operate said actuating lever to positively drive said print hammer through a predetermined portion of its stroke, said resilient means enabling said print hammer to move away from said actuating lever to travel the last portion of its stroke by momentum against the influence of said resilient means.

4. In a printing telegraph apparatus, a plurality of type elements, a type operating member for operating said elements, said member having a slot, actuating means for said member having a pin engageable in said slot, resilient means for urging the slotted portion of said operating member into engagement with the pin of said actuating means, and means to operate said actuating means to positively drive said type operating member through a portion of its stroke, said resilient means enabling the slotted portion of said type operating element to move away from the pin of said actuating means to thereby enable said type operating member to travel the last portion of its stroke under momentum against the influence of said resilient means.

5. In a printing telegraph apparatus, a plurality of type elements, a type operating member for operating said elements, said member having a slot, actuating means for said member having a stud engageable in said slot, spring means for urging the slotted portion of said operating member into engagement with the stud of said actuating means, and cam controlled means to operate said actuating means to positively drive said type operating member through a portion of its stroke, said spring means enabling the slotted portion of said type operating element to move away from the stud of said actuating means to thereby enable said type operating member to travel the last portion of its stroke under momentum against the influence of said spring means.

CARL A. LEVIN.
